UNITED STATES PATENT OFFICE.

HENRY S. JEWELL AND FREDERICK C. JEWELL, OF CHICAGO, ILLINOIS.

COIN-CONTROLLED VENDING MECHANISM.

Application filed January 22, 1923. Serial No. 614,235.

To all whom it may concern:

Be it known that we, HENRY S. JEWELL and FREDERICK C. JEWELL, citizens of the United States, residing at Chicago, in the 5 county of Cook and State of Illinois, have invented new and useful Improvements in Coin-Controlled Vending Mechanisms, of which the following is a specification.

Our invention relates to machines for 10 vending merchandise, such as boxes of safety matches, chewing gum and the like, the same being stacked in the machine and ejected therefrom by a coin controlled mechanism, the primary object of the invention being to provide a novel and improved coin 15 controlled vending mechanism which is operable only upon the deposit of the proper coin or token and which is provided with a means to prevent recovery of such coin or 20 token after a partial actuation of the mechanism.

A further object of the invention is the provision with a machine of this kind of an 25 improved vending device whereby removal of the merchandise from the machine is prevented except upon deposit of the proper coin.

A still further object of the invention is to furnish a vending mechanism which is 30 relatively simple in construction, highly efficient and positive in operation, and which will be strong and durable.

With the above and other objects in view as will become more apparent as the 35 description proceeds, the invention comprises a novel combination and arrangement of parts to be hereinafter described and claimed, and in order that the same may be better understood, reference is had to the accompanying drawing forming a part of this specification.

In the drawing,

Figure 1 is a sectional elevation of a portion 45 of a vending machine constructed in accordance with our invention, the coin controlled mechanism being shown in side elevation;

Fig. 2 is a bottom plan view illustrating the vending mechanism of the unit shown in 50 Fig. 1;

Fig. 3 is a section on the line 3—3 of Fig. 1, and

Fig. 4 is a vertical section taken through 55 one of the vending units, and illustrating a slightly modified form of delivery device for vending chewing gum.

Referring now specifically to the drawing wherein like reference characters designate like parts throughout the several views, numeral 5 denotes a portion of the vertical housing of a vending machine, said housing being supported upon a base plate 9 which forms the cover for the coin receptacle 8. Within the housing 5 are positioned a plurality of vertically disposed channelled holders for receiving the stacks of packages to be vended. In the drawing only two of these units are illustrated, numeral 6 denoting a unit for receiving boxes of safety matches 7, while the unit 6^a is 70 shown for receiving sticks of chewing gum 7^a.

Coming now to the vending mechanism and referring particularly to Figs. 2 and 4, it will be noted that the plate 9 is provided 75 with a plurality of longitudinal recesses 10 in its rear edge extending a substantial distance toward the front of the machine and in each of which, one unit of the actuating and delivering portion of the mechanism 80 slides, this portion of the mechanism comprising a push bar 11 of flat sheet metal extending forwardly beneath the bottom surface of the base plate 9 and the rear end of which is vertically offset as shown at 12, so 85 that the side edges of such offset portion will slide in the recess 10 of the plate 9. Upon this vertically offset portion 12 of the push bar 11 is mounted a match box delivering device A, or a chewing gum delivering device B as the case requires, it being noted that the forwardly extending portions of the delivery devices A and B extend beyond the vertically offset portion 12 and above the plate 9 as best illustrated in Figs. 3 and 95 4, this construction serving to hold the push bar 11 and the delivery devices in sliding engagement with the plate 9. Referring to Fig. 1 it will be seen that the match box delivery device is provided with an offset rearward extension A¹, the function of which is to support the stack of boxes when the delivery device is in its normal or partially extended position as shown in the drawing. The forward portion of the delivery device 105 A terminates in vertical fingers A², the purpose of which is to prevent unauthorized removal of the boxes after the vending device has receded within the channelled receiver 6. It will be evident that upon pushing the 110 push bar 11 the delivery device A will be carried within the channelled receiver 6 and

a match box 7 will drop into the receiver for delivery to the customer, the front and rear portions of the channeled receiver 6, and the front portion of the vertical housing 5 of the machine having openings 13 and 15 therein to permit the insertion and recession of the vending device A. In Fig. 4, the chewing gum vending device B is shown with a back turned portion B' which lies in the same plane with the upper face of the body portion of the device in close proximity thereto and upon which the stack of gum normally rests. When the push bar 11 is actuated, the rear end of the delivery device B will be projected through the cut away portion 15^a in the back of the channeled receiver 6^a so that it will slide from beneath the stack of gum which now rests upon the device B. Upon recession of the delivery device B the forward end of the back turned portion B' will engage the rear longitudinal edge of the lowermost stick of chewing gum which has dropped upon the upper face of the device and will carry it forwardly out through the openings 14 in the forward portion of the channeled receiving member and in the front wall of the housing for delivery to the customer the back turned portion B' during this operation inserting itself beneath the next higher stick of gum 7^a. It will be noted that the front end of the delivery device B has an upturned lip B^a the purpose of which is to prevent unauthorized removal of the sticks of chewing gum from the delivery device when it has been fully inserted into the housing for engagement of a stick of chewing gum. Since the channeled receiving member 6^a is considerably narrower than the unit 6 for receiving match boxes, a flange or spacing member 16 is shown carried by the front of the housing 5 to maintain the channeled receiving member 6^a in proper position with respect to the other portions of the apparatus.

In order to cooperate with the extended portion of the delivery devices A and B in maintaining the push bar 11 in sliding contact with the plate 9, we have provided at the front portion of said plate in alignment with each recess 10, a metal strap 17 for bridging the under portion of said push bar 11, which strap is plainly shown in Fig. 3. Bridging this strap 17 is a second strap 18 having apertures in the ends thereof. Upon the under surface of the vertically offset portion 12 of the push bar 11 is secured a metal cross strip 19, the laterally bent ends 19^a of which are apertured to receive the ends of coil springs 20, the free ends of which are secured in the apertures in the ends of the straps 18. By this construction it will be seen that upon pressing the push bar 11 inwardly to permit the delivery device to receive the article to be vended there is a normal tendency of the bar to recede

and bring the delivery device again to vending position.

Coming now to the coin controlled feature of the mechanism, it will be seen that the push bar 11 carries upon its under surface 70 within the coin receptacle 8 a coin receiver 21 which is riveted thereto as shown at 21^a. The coin receiver 21 is open at the bottom, its construction being best shown in Fig. 2. A coin 23 may be inserted into the coin receiver 21 through registering slots 22 in the plate 9 and the push bar 11, said slots being in registry when the mechanism is in its normal position preparatory to operation as shown in Figs. 1 and 4. The coin 23 having 75 been inserted into the coin receiver 21, is supported by the arcuate laterally projecting portion of a plate 27 to be referred to more specifically hereinafter. Toward the rear of the plate 9 and bridging a portion of 80 the recess 10 is a strap 24, to the under surface of which is pivoted an arm 25 as shown at 26 in Figs. 1 and 2. Carried by the arm 25 and projecting downwardly and laterally from the inner edge thereof is the arcuate 85 coin supporting plate 27 above referred to, this plate being broken away in Fig. 2 to show the coin receiver 21. Upon the upper surface of the arm 25 and extending beyond the forward end thereof above, and in sliding engagement with the upper surface of the strap 18 is a finger 28 which, with the plate 27 is secured to arm 25 by means of rivets or screws 27^a. The inner longitudinal edge of the finger 28 is formed with teeth 29 which cooperate with a stud 30 upon the under surface of the push bar 11 to prevent advancement of the same by unscrupulous persons who have not deposited a coin in the slot. The inner longitudinal edge of the 90 arm 25 is also formed with teeth 31, but these teeth are directed toward the rear of the arm, whereas the teeth of the finger 28 are forwardly directed. The forward end of the arm 25 is reduced and its inner edge 95 leading to the teeth 31 is formed with a cam surface as best shown in Fig. 2. It will thus be seen that when a coin 23 has been placed in the coin receiver 21 it extends beyond the open inner edge of said receiver and engages the inner forward edge of the arm 25, and upon insertion of the push bar 11 the edge of said coin 23 slides backward against the cammed surface to cause the arm 100 25 to swing outwardly to remove the teeth 29 of the finger 28 from the path of the advancing stud 30, thus permitting the full insertion of the push bar 11. The inner edge of the arm 25 near the pivot 26 is provided 105 with an apertured ear 32 in which is secured a spring 33, the free end of said spring being located in an aperture 34 of the strap 24. Fig. 2 illustrates that one side of the coin receiver and carrier 21 is open to permit the coin to engage the cam surface on 110

the edge of the arm 25 at the forward portion thereof.

It will be evident that the rearwardly directed teeth of the arm 25 coast with the 5 edge of the coin 23 to prevent withdrawal of the push bar 11 until the coin has reached the end of the supporting plate 27 and has dropped therefrom into the coin receptacle 8.

From the foregoing description read in 10 connection with the accompanying drawings it is thought that the novel features and advantages of our invention will be readily appreciated.

In accordance with the patent statutes we 15 have illustrated our invention in concrete form, and described it as operating in a specified manner, but it will be distinctly understood that we do not intend to limit ourselves strictly thereto, since various changes 20 will suggest themselves to those skilled in the art without departing from the spirit of the invention, the scope of which is defined by the following claims.

Having thus described our invention, what 25 we claim as new and desire to secure by Letters Patent is:—

1. A coin-controlled mechanism comprising a supporting member having a coin receiving slot, a slideable bar beneath said supporting member, a coin receiver and carrier movable with and rigidly secured to the under side of said bar and adapted for registration with said slot, an arm pivotally supported beneath said bar and having a 35 coin supporting member beneath said coin receiver and carrier to hold the coin in said carrier during a portion of the movement of said bar, said arm being provided with ratchet teeth, and a lug on said bar to engage 40 said teeth, said arm being provided with a coin engaged cam surface whereby the arm is swung on its pivot during the movement of the bar in one direction.

2. The construction set forth in claim 1, 45 and a bar guiding means carried by said supporting member and engaged by said lug to limit the outward movement of said bar.

3. The construction set forth in claim 1, 50 said arm being provided with a second set of ratchet teeth engaged by the coin during its movement on said coin supporting member.

4. The construction set forth in claim 1, 55 and a strap secured to said bar and having its ends extended beyond the bar into engagement with said supporting member.

5. A coin-controlled mechanism comprising a supporting member having a coin receiving slot, a slideable bar beneath said supporting member, a coin receiver and carrier movable with and rigidly secured to the under side of said bar and adapted for registration with said slot, an arm pivotally supported beneath said bar and having a coin supporting member beneath said coin receiver and carrier to hold the coin in

said carrier during a portion of the movement of said bar, said arm being provided with ratchet teeth, a lug on said bar to engage said teeth, said arm being provided with a coin engaged cam surface whereby the arm is swung on its pivot during the movement of the bar in one direction, said arm being provided with a second set of ratchet teeth engaged by the coin during its movement on said coin supporting member, a strap secured to said bar and having its ends extended beyond the bar into engagement with said supporting member, and springs connected to the ends of said strap and urging the bar outwardly.

6. A coin-controlled mechanism comprising a supporting member having a coin receiving slot, a slideable bar beneath said supporting member, a coil receiver and carrier rigidly connected to the under side of said bar and having its lower end and one side open whereby a coin positioned in the receiver and carrier will extend beyond one side of the same, an arm pivotally supported beneath said bar and having a coin engaged cam surface, said arm also being provided with a coin supporting member located beneath said coin receiver and carrier to hold the coin in said carrier during a portion of the movement of said bar, said arm being provided with ratchet teeth adapted for engagement by said coin, and a lug on said bar, said arm being provided with a second set of teeth for engagement by said lug.

7. A coin-controlled mechanism comprising a supporting member having a coin receiving slot, a slideable bar beneath said supporting member, a coin receiver and carrier rigidly connected to the under side of said bar and having its lower end and one side open whereby a coin positioned in the receiver and carrier will extend beyond one side of the same, an arm pivotally supported beneath said bar and having a coin engaged cam surface, said arm also being provided with a coin supporting member located beneath said coin receiver and carrier to hold the coin in said carrier during a portion of the movement of said bar, said arm being provided with ratchet teeth adapted for engagement by said coin, a lug on said bar, said arm being provided with a second set of teeth for engagement by said lug.

8. The construction set forth in claim 1, 105 and a bar guiding means carried by said supporting member and engaged by said lug to limit the outward movement of said bar.

9. The construction set forth in claim 1, 110 said arm being provided with a second set of ratchet teeth engaged by the coin during its movement on said coin supporting member.

10. The construction set forth in claim 1, 115 and a strap secured to said bar and having its ends extended beyond the bar into engagement with said supporting member.

11. A coin-controlled mechanism comprising a supporting member having a coin receiving slot, a slideable bar beneath said supporting member, a coin receiver and carrier movable with and rigidly secured to the under side of said bar and adapted for registration with said slot, an arm pivotally supported beneath said bar and having a coin supporting member beneath said coin receiver and carrier to hold the coin in

sliding member, said runway operating to limit the passage of a coin through the chute, means for normally maintaining the swinging member in one position, coacting means carried by both of the members for holding the sliding member against movement when the swinging member is in its normal position, said swinging member being provided with means for coaction with a check within the chute for moving said swinging member into a position to release the sliding member.

9. In a check controlled apparatus, a member supported for sliding movement, a second member supported for swinging movement and positioned adjacent the sliding member, a check chute carried by the sliding member and disposed toward the swinging member, a runway carried by the swinging member and underlying the chute during a portion of the movement of the sliding member, said runway operating to limit the passage of a coin through the chute, means for normally maintaining the swinging member in one position, coacting means carried by both of the members for holding the sliding member against movement when the swinging member is in its normal position, said swinging member being provided with means for coaction with a check within the chute for moving said swinging member into a position to release the sliding member, said swinging member having disposed therealong a series of ratchet teeth

facing a pivotal mounting of the swinging member.

10. In a check controlled apparatus, a member supported for sliding movement, a second member supported for swinging movement and positioned adjacent the sliding member, a check chute carried by the sliding member and disposed toward the swinging member, a runway carried by the swinging member and underlying the chute during a portion of the movement of the sliding member, said runway operating to limit the passage of a coin through the chute, means for normally maintaining the swinging member in one position, coacting means carried by both of the members for holding the sliding member against movement when the swinging member is in its normal position, said swinging member being provided with means for coaction with a check within the chute for moving said swinging member into a position to release the sliding member, said swinging member having disposed therealong a series of ratchet teeth facing a pivotal mounting of the swinging member, said swinging member being also provided with a series of oppositely facing teeth comprised in the coacting means for holding the sliding member against movement.

In testimony whereof we affix our signatures.

FREDERICK C. JEWELL.
HENRY S. JEWELL.
